CLAIM

The ornamental design for a dust collecting box, as shown and described.

DESCRIPTION

FIG. 1 is a front perspective view of a dust collecting box, showing my new design;
 FIG. 2 is a rear perspective view thereof;
 FIG. 3 is its folded state diagram;
 FIG. 4 is a front view of the design shown in FIG. 2;
 FIG. 5 is a rear view thereof;
 FIG. 6 is a left side view thereof;
 FIG. 7 is a right side view thereof;
 FIG. 8 is a top view thereof; and,
 FIG. 9 is a bottom view thereof.
